ROAD GRADER

Franklin E. Arndt, Galion, Ohio, assignor to The
Galion Iron Works & Manufacturing Company,
a corporation of Ohio

Application July 31, 1940, Serial No. 348,981

2 Claims. (Cl. 37—156)

My invention relates to road graders, and one of its objects is the provision of improved, very flexible and efficient means for angularly adjusting a road working implement relative to the road surface.

Another object of the invention is the provision of improved and efficient means for laterally shifting a road working implement in a road grader.

Another object of the invention is the provision of a rotary fluid-pressure motor connected through self-locking worm gearing to laterally shifting mechanism for a grader blade in a road grading machine, with the self-locking worm gearing effective to hold the grader blade in adjusted lateral position.

Other objects of the invention will appear hereinafter, the novel features and combinations being set forth in the appended claims.

In the accompanying drawings,

Figs. 1 and 2 placed end to end, show a power road grader embodying my improvements;

Fig. 3 is a plan view taken on the line 3—3 of Fig. 2;

Fig. 4 is a plan view of a portion of Fig. 3 but with the low pitch worm gearing shown more in detail;

Fig. 5 illustrates the connections for the laterally shifting mechanism shown at the upper left-hand portion of Fig. 2;

Fig. 6 is an enlarged right-hand end elevation of the left-hand portion of Fig. 5, to illustrate the worm gearing connections to the laterally shifting arm;

Fig. 7 is an enlarged sectional elevation of the gearing for operating the circle;

Fig. 8 is a piping diagram for the rotary hydraulic motors shown in Figs. 4 and 5;

Fig. 9 is a sectional elevation of the rotary hydraulic motor for operating either the circle or the laterally shifting mechanism;

Fig. 10 is a sectional plan view of the left-hand portion of Fig. 9 taken on the center line of the motor;

Fig. 11 is a sectional elevation taken on the line 11—11 of Fig. 9 looking in the direction of the arrows;

Fig. 12 is a sectional elevation taken on the line 12—12 of Fig. 9 looking in the direction of the arrows;

Fig. 13 is a sectional elevation similar to Fig. 9 but illustrating a modified motor which may be used for rotating the circle or for operating the laterally shifting mechanism;

Fig. 14 is a plan view of the left-hand portion of Fig. 13;

Fig. 15 is a sectional elevation taken on the line 15—15 of Fig. 13, looking in the direction of the arrows; and

Fig. 16 is a sectional elevation taken on the line 16—16 of Fig. 13, looking in the direction of the arrows.

Referring to Figs. 1 and 2 placed end to end it will be seen that the grader frame 17 is mounted at its rear end on an axle frame 18 carrying the internal combustion engine 19 which is connected through dual driving mechanism to the ground engaging traction wheels 20, 20, said axle frame 18, engine 19 and wheels 20 being connected together and forming a tractor or power traction unit to propel the grader. The front end of the grader frame or vehicle frame 17 is mounted on a steering wheel unit 21 connected through a steering mechanism 22 to a reciprocating steering hydraulic motor 23. The latter is connected between the frame 17 and the steering mechanism 22 and is controlled by a valve having an operating lever at the operator's station 24. That is to say, the operator while on his seat 24 may turn the steering wheel 25 to actuate valve mechanism which is connected to the hydraulic motor 23 to effect steering of the machine. The operator at his station as shown in Fig. 1 has before him all of the various levers for not only steering the machine but also controlling the operation of the engine and the various adjustments in the road grader.

The drawbar frame 26 as shown in Fig. 2 is flexibly connected at 27 to the front end of the grader frame 17. The rear end of the drawbar 26 has a crosspiece 28 to the ends of which are connected by means of ball and socket joints 29, 29, the lower ends of the extensible hangers 30, 30, the upper ends of which are connected by ball and socket joints 31, 31 to the laterally extending arms 32, 32 which are connected to the longitudinally extending rock shafts 33, 33 journaled in the bearings 34, 34 shown in Fig. 3 one on each side of said frame 17. The rear ends of the rock shafts 33 are mounted in similar bearings and are connected to laterally extending arms flexibly connected to the upper ends of piston rods 35 of a pair of double acting hydraulic motors 36, 36. From the operator's station 24 either or both of the piston reciprocating hydraulic motors 36 may be operated to lift or lower the hangers 30, 30 individually and thus adjust the elevation of the drawbar 26 and its inclination transversely of the road surface.

Carried by the drawbar frame 26 for rotation relatively thereto is a circle 37 carrying the moldboard 38 and the latter's cutting blade 39. The circle 37 carries an annular gear 40 which meshes with the pinion 41 secured to the lower end of the shaft 42, the upper end of which is keyed at 43 to the worm gear 44, the latter being enclosed in a casing 45, as shown in Fig. 7.

The casing 45 is provided with a lower cylindrical extension 46 resting on the top of the pinion 41 as shown in Fig. 7. A bearing bushing 47 lines the cylindrical extension 46. The latter has secured thereto brackets 48 which are provided with upper and lower flanges both at the front and at the rear for bolting by means of the bolts 49, 49 to the upright supporting plates 50, 50 which are secured rigidly as cross-pieces to the drawbar frame 26, as shown in Fig. 3.

Also mounted within the casing 45 is a worm 51 in position to mesh with the worm gear 44. While the pinion 41 may be welded to the shaft 42 as indicated at 52 in Fig. 7, the upper end of the shaft 42 is screw-threaded to receive the nut 53 and the nut locking pin 54.

Mounted on a horizontal plate 55 at the forward end of the drawbar frame 26 is a rotary hydraulic motor 56, the interior construction of which may be as shown in Figs. 9 to 12, inclusive. The shaft 57 of the motor 56 extends rearwardly longitudinally of the center line of the drawbar frame 26 and is connected by means of the universal joint 57' to the shaft 58, the rear end of which in turn is connected by means of the universal joint 59 to the shaft 60 of the worm 51.

An important feature of my invention is the provision of relatively low pitch worm gearing 44, 51 so as to be operable with considerable power in rotating the circle against such resistances as may be encountered by the grader blade 39 in contact with the road surface. The worm gearing being of low pitch is self-locking and therefore eliminates the use of the usual pin and hole locking mechanism to hold the circle in adjusted position relative to the drawbar. For example, I have in commercial machines used worms 51 each having a pitch of .75". That is to say, the worms have been single cut with the leads of .75". The worm gears 44 meshing with such worms in such commercial structures, have each been single cut circular pitch .75" with forty-two teeth. Further, in such commercial structures the spur pinions 41 each has six teeth of the circular pitch of 2.618" and this arrangement rotates the circle which has a pitch diameter of 52" and sixty-five teeth; that is to say, 1.25 diametral pitch or 2.5138 circular pitch. The ratio of the gearing between the motor shaft 57 and the circle 37 in such commercial structures is approximately 455 to 1. These dimensions and the ratio may of course be varied as desired, but the figures are set forth merely by way of example to show that the hydraulic motor 56 must rotate its shaft 57 a great many times to rotate the circle once. In the illustration given, the shaft 57 rotates 455 times to secure one rotation of the circle. A complete rotation of the circle, however, is seldom necessary and is desired only when the grader blade 39 is to be reversed from the position shown in Fig. 2 and the grader operated by backing the same or traveling rearwardly. During ordinary operations in practice the circle may be shifted about 90° to adjust the machine from a right-handed working machine to a left-handed working machine and vice versa. But even a quarter

of a rotation of the circle 37 would require about 114 rotations of the shaft of the hydraulic motor 56.

The speed of the hydraulic motor 56 may be controlled by the operator at his station 24 by actuating the lever 61 of the manifold valve 62 shown in Fig. 8. The hydraulic pump 63 is driven by means of the V-belt gearing 64 shown in dotted lines in Fig. 1, which gearing is connected to the internal combustion engine 19 by means of a take-off therefrom. As shown in Fig. 8, a suction pipe 65 extends into the supply tank 66. A supply pipe 67 is connected through a high pressure relief valve 68 to the return line 69. The high pressure relief valve 68 opens in the direction of the arrow 70. By operation of the valve lever 61 supply pressure may be directed into either pipe 71 or 72 and the other pipe then acts as the return pipe. In this manner, the direction of flow through the motor 56 will determine the direction of rotation of the latter, and the rotation of the motor shaft 57 determines the direction of rotation of the circle which carries the moldboard. It will thus be seen that the speed of the hydraulic motor 56 is controlled by the amount of oil which the pump is permitted to deliver to the motor 56. The speed of the motor 56 can be slowed down by throttling action of the valve in the manifold 62. The hydraulic motor 56 used in the commercial structures referred to, can rotate at approximately 145 revolutions per minute and it will thus be seen that the circle can be rotated through approximately 90° in less than a minute. However, I wish to repeat that this reference is made merely by way of example to show the relatively high speed of rotation of the motor 56 and not the exact speed thereof as in any event the operator at his station may so operate the valve lever 61 as to secure a slower rotation of the motor so as to adjust the moldboard to certain definite angles relative to the line of draft of the road grading machine.

The mechanism for laterally shifting the moldboard and laterally shifting the rear end of the drawbar frame 26 is shown in Figs. 2, 3, 5 and 6. An extensible link 73 is connected to a universal joint 73' near one end of the cross-piece 28, as shown in Fig. 3. The other end of the extensible link 73 is connected by means of the universal joint 74 to the lower end of the laterally swinging arm 75. The ball 74' of the universal joint 74 is shown in Figs. 2, 5 and 6.

The upper end of the arm 75 is keyed to the rock shaft 76 the axis of which extends longitudinally of the grader and between and below the axes of rock shafts 33, 33 and which is journaled in the bearing 77 mounted on the bracket 78 secured to the cross-plate 79 between the forwardly converging members 80, 80 of the supporting frame 81.

The rock shaft 76 may also be journaled in the bearing 82 secured to the plate 79. The rear end of the rock shaft 76 is keyed to a worm gear 83 which meshes with the worm 84. The worm 84 and worm gear 83 may be mounted in the casing 85 which is secured to the vertical plate 86, the ends of which are welded to the converging members 80, 80 of the frame 81.

The shaft 87 of the worm 84 is connected to a worm gear 88 in the casing 89, as shown in Fig. 6. The worm gear 88 meshes with another worm 90 on the shaft 91, as shown in Figs. 5 and 6. By means of the universal joint 92 the shaft 91 is connected to the inclined shaft 93 which in turn

is connected by means of the universal joint 94 to the shaft 96 of the hydraulic motor 97.

Both the worm gearing 84, 83 and the worm gearing 90, 88 are relatively low pitch so that many rotations of the motor shaft 96 will be necessary to move the arm 75 through a small angle. Such low pitch gearing enables the laterally shifting mechanism to be operated with considerable power so that the moldboard may be shifted laterally of the road surface even though the scraping blade may be in contact therewith. Inasmuch as the motor 97 is of relatively high speed under the control of the operator at his station 24, the lateral shifting of the moldboard may be effected in a short space of time. By means of the valve handle 98 shown in Fig. 8, the motor 97 may have directed to it through the pipes 99 and 100 the supply and return flow of the oil or other fluid-pressure medium. The motor 97 may be reversed or controlled to operate in either direction, and therefore the arm 75 may be swung laterally of the vehicle frame either toward one side or toward the other side and consequently the grader blade with the assistance of adjustment of the extensible links or hangers 30, 30, may be adjusted to bank-sloping position at either side of the machine.

While the frame 81 may be connected to and extend forwardly from the dashboard 101 of the power traction unit 19, it should be understood that the forward end of the frame 81 is rigidly connected to the spaced-apart side members of the vehicle frame 17. The motor 97 may be mounted on the cross-plate 102 between extensions 103, 103 from the converging members 80, 80. I prefer, however, to mount the motor rigidly on a cross-piece 104 rigidly attached to the tops of the spaced-apart channels of the main frame 17, as shown in Fig. 2.

In advance of the moldboard a scarifier 105 mounted on a frame 106 pivoted at 107, may be adjusted by means of the hangers 108 on opposite sides of the machine. Such hangers 108 are similar to the hangers 30, 30 as to including a rod 109 telescoping into a tube 110 and held in position by pin 111 fitting in registering holes.

The upper ends of the hangers 108 are connected to bell cranks 112 pivoted at 113 to the vehicle frame 17. A reciprocating hydraulic motor 114 is pivoted at its rear end to the bracket 115, and its piston plunger 116 is pivoted at 117 to the bell cranks 112. The pair of motors 36, the steering motor 23 and the scarifier motor 114 may be controlled by the operator at his station at the manifold similar to that designated at 62 in Fig. 8 by adding valves for the control of the piston motors as well as the rotary motors.

The rotary motor 56 shown in Fig. 9 comprises a cylinder 118 to the ends of which are secured the end plates 119 and 120. The plate 119 is secured to the cylinder 118 by means of the circumferentially spaced cap screws 121, 121. The plate 120 is secured to the other end of the cylinder 118 by means of the circumferentially spaced cap screws 122, 122.

Within the casing 118 is a bearing block 123 which is provided with an annular shoulder 124 which fits against the inner face of a circular opening in the end plate 119. The left-hand end of the bearing block 123 is screw-threaded to receive the nut 125 which when tightened in place against the end plate 119, holds the bearing block 123 rigidly connected in adjusted position to the end plate 119. The bearing block 123 is preferably keyed at 123' to the end plate 119.

Journalized on the bearing block 123 is a cylinder block 126 which is provided with a plurality of circumferentially spaced cylinders, in this instance five in number. These cylinders may be formed by boring entirely through the block from end to end and axially thereof and then providing the left-hand ends of each of the bores with screw threads to receive the screw-threaded plugs 127, 127, as shown in Fig. 9.

10 Radial drain openings may also be bored and closed by screw-threaded plugs 128, 128. Solid pistons 129, 129 fit into the cylinders for reciprocation relatively to the cylinder block 126 along lines parallel to the axis thereof.

15 The outer ends 130, 130 of the pistons 129 have the shape of a frustum of a cone and are adapted to bear against the thrust plate or swash plate 131, the center of which is provided with a large opening 132 through the cylindrical extension 133. Surrounding the cylindrical extension is a ball bearing race 134.

20 Connected to the inner side of the end plate 120 preferably by being made integral therewith, is a swash plate box or thrust block 135 having an annular seat 136 for receiving the bottom of the outer ball bearing race 137. The outer cylindrical surface of the outer ball bearing race 137 fits a corresponding cylindrical seat 138 in the swash plate box 135. A plurality of circumferentially arranged balls 139, 139 completes the ball bearing between the swash plate or thrust plate 131 and the thrust block or swash plate box 135.

25 The left-hand end of the cylinder block 126 fits against a thrust ball bearing 140 which in turn is seated against the annular shoulder 141 on the stationary bearing block 123.

30 The pipes 71 and 72 shown in Fig. 8 are screw-threaded into the left-hand end of the bearing block 123 for communication to the passageways 142, 143 which lead inwardly to the ports 144 and 145 for registry one after another with the ports 146, 146 which lead to the cylinders 129', 129', as shown in Fig. 11. The ports 146 may be bored radially and then closed by means of the screw plugs 128, 128, as shown in Fig. 11. As shown in Fig. 11 which is a sectional view taken on the line 11-11 of Fig. 9 looking in the direction of the arrows, two of the cylinders 129' are in communication with the pipe 72 and two other cylinders 129' are in communication with the other pipe 71, while the lowermost cylinder is not in communication with either pipe 71 or 72.

35 The right-hand end of the cylinder block 126 is splined at 147 to the shaft 57, the outer end of which is adapted to be pinned at 148 to the universal joint 57' shown in Fig. 2.

40 An annular shoulder 149 on the shaft 57 fits against the inner race of a ball bearing 150, the outer race of which fits into an annular recess on the inside of the end plate 120. Inasmuch as the chamber 151 in the casing of the hydraulic motor may be filled with oil, it is desirable to provide an oil seal at 152 in the form of a stuffing box having members spring-pressed between the inner race 45 of the ball bearing 150 and the cap plate 153 in which the shaft 57 is journaled. The cap plate 153 may be secured by means of the machine screws 154, 154 to the cylindrical extension 155 from the outer side of the plate 120. Within the cylinder block 126 is a chamber 156 which communicates with the chamber 151 through the openings 157, 157.

45 It should be understood that either of the ports 144 or 145 may be the supply port and the other

the exhaust port. In other words, either the pipe 71 or the pipe 72 may be the supply line and the other pipe the return line. Due to leakage along the pistons 129 on the supply pressure side of the motor, an undesirable pressure may be built up in the chamber 151 and it is highly desirable that such built-up pressure is provided with relief. For this purpose the passageways 142 and 143 are extended as shown at 158 and 159 in Fig. 10 for connecting the passageways 142 and 143 to the chamber 156. At the right-hand end of the passageways 158 and 159 are mounted ball check valves 160, 161 which open from the chamber 156 but close automatically when pressure is exerted in tending to cause a flow from the passageway 158 into the chamber 156. However, one of the passageways 158 or 159 is always an exhaust passageway and therefore built-up pressure in the chamber 151 may easily be relieved by the check valve opening from the chamber 156 into the exhaust passageway. For instance, if the passageway 158 is connected to the supply pipe 71, the check valve 160 will be held closed by the supply pressure. The built-up pressure in the chamber 151 will open the check valve 161 for flow of oil from the chamber 156 into the exhaust passageway 159 to the return pipe 72.

The hydraulic motor 56 may be detachably mounted on the plate 55 (Figs. 2 and 4) by means of screws inserted through the plate 55 into screw-threaded openings in the feet 162, 162 shown in Figs. 9 and 12. In a similar manner, the motor 97 may be detachably mounted on its supporting plate 104 by means of screws inserted through openings therein into the screw-threaded openings 163, 163 in the feet 164, 165 shown at the bottom of the casing 166 in Figs. 13, 15 and 16.

The modified motor shown in Figs. 13 to 16, inclusive, is composed of a cylinder block 167 which remains in stationary position during operation of the motor. As shown in Fig. 15, which is a sectional elevation taken on the line 15-15 of Fig. 13 looking in the direction of the arrows, the pistons 168 fit in cylinders 169 each of which may be formed by boring and counter-boring and then closing the left-hand ends as viewed in Fig. 13 with screw plugs 170, 170. The radial ports 171, 171 may be formed by radial boring, with the outer ends closed by the screw plugs 172, 172. The right-hand ends 173 of the pistons 168 each has the shape of a frustum of a cone in position to engage the thrust plate 174 mounted by means of the thrust ring roller bearing 175 on the tilted thrust block 176 which is keyed at 177 to the shaft 178. The thrust plate 174 is held to an annular seat 179 on the thrust block 176 by means of the ring plate 180 held in place by the cap screw 181 extending through the plate 180 into the screw-threaded opening in the block 176, as shown in Fig. 13.

The left-hand end of the block 176 as shown in Fig. 13, fits against an annular shoulder 182 on the shaft 178 while the right-hand end of the thrust block 176 rests against the inner race of a roller thrust bearing 183 surrounding a reduced portion 184 of the shaft 178. A further reduced portion 185 extends through a liquid seal 185 comprising a spring-pressed stuffing box held in place by the cap 186 and the screws 187, 187.

An enlarged portion 188 of the shaft 178 has an annular shoulder fitting against the inner race 189 of the ring thrust bearing 190, the outer race 191 of which fits against an annular shoulder surrounding the chamber 192 within the cyl-

inder block. It will thus be seen that endwise movement of the shaft 178 relative to the motor frame or casing is resisted by the oppositely arranged thrust bearings 183 and 190.

5 The inner end of the shaft 178 is keyed at 193 to a reduced extension of the cylindrical port block 194 which by reason of its connection to the shaft 178 rotates with the latter during operation of the motor.

10 The pipes 99 and 100 of Fig. 8 are adapted to be connected to the screw-threaded ports 99' and 100' shown in Fig. 14. The port 99' communicates with the cylindrical port 195 which is located in the cylinder block and completely surrounds the rotating cylindrical port block 194. In a similar manner, the port 100' communicates with the circular port 196 which is located in the cylinder block and completely surrounds the cylindrical port block 194.

15 In the cylindrical port block are two radial openings 197 and 198 on opposite sides as shown in Fig. 13. The ports 197 and 198 communicate with separate passageways 199 and 200 in the cylindrical port block 194. The passageways 199 and 200 are parallel to each other and parallel to the axis of rotation of the shaft 178. These passageways lead toward the left as viewed in Fig. 13 and respectively communicate with the ports 201 and 202. Each of the passageways 199 and 200 may be formed by boring and their left-hand ends closed by screw plugs as illustrated at 203 in Fig. 13.

20 As shown in Fig. 15, the port 100' is in communication with the ports 196, 197, 199, 201, and two of the cylinders 169 at the lower right-hand portion of Fig. 15. The other port 99' communicates with the ports 195, 198, 200 and 202, thereby communicating with the cylinders 169 at the lower left-hand portion of Fig. 15. The uppermost cylinder is cut off when the port block 194 is in the position shown in Fig. 15.

25 As shown in Fig. 13, a cap plate 204 is secured in place by means of the screws 205, 205 to close the cylindrical opening in which the cylindrical port block 194 rotates. A passageway 206 extends axially through the port block 194 so that oil-escaping into the chamber 207 may flow into the main chamber 208 of the motor. The right-hand end of the motor may be provided with an inspection opening normally closed by means of the screw plug 209.

30 It is important to note that two separate parallel passageways 210 and 211 lead respectively from the ports 99' and 100' into the chamber 208. The passageways 210 and 211 are parallel to each other and parallel to the axis of rotation of the shaft 178. The passageway 211 leads from the chamber 208 to the port 100' and is therefore seen in full lines in Fig. 16 which is a section taken on the line 16-16 of Fig. 13 looking in the direction of the arrows. The other passageway 210 is shorter, as may be seen in the elevational view of Fig. 13.

35 The right-hand ends of the passageways 210 and 211 are each provided with a check valve 212, 212 which are so arranged as to open from the chamber 208 into the passageways 210 and 211. In other words, when either port 99' or 100' is a supply port, the check valve connected thereto remains closed by supply pressure, while the other check valve connected to the exhaust automatically opens to relieve the chamber 208 of built-up pressure therein due to leakage past the pistons or otherwise.

40 In both the form of rotary motor shown in

Figs. 9 to 12, inclusive, and in the form shown in Figs. 13 to 16, inclusive, the motor mechanism is entirely enclosed and no return pipes to the supply tank are included aside from those already described in connection with Fig. 8. The check valves in the motors assure maintaining the chambers 151 and 208 filled with oil for lubricating purposes and the interior pressure is limited by the check valves. In other words, the check valves obtain these advantages which are particularly desirable in road graders because the rotary motors are widely spaced from the operator's seat 24 under which the supply tank 66 is located, as shown in dotted lines in Fig. 1.

The hydraulic motor per se herein disclosed is claimed in my divisional application, Serial No. 379,971, filed February 21, 1941, for an improvement in road graders.

Obviously those skilled in the art may make various changes in the details and arrangement of parts without departing from the spirit and scope of the invention as defined by the claims hereto appended, and I therefore wish not to be restricted to the precise construction herein disclosed.

Having thus described and shown an embodiment of my invention, what I desire to secure by Letters Patent of the United States is:

1. In a road grader, the combination with a vehicle frame, of a drawbar flexibly connected at its forward end to the forward end of said frame, a grader blade carried by said drawbar, means for adjusting said drawbar relative to said frame, a longitudinal shaft mounted on said frame for rocking movement relatively thereto, and actuating arm on said shaft, a link connecting said arm to said drawbar, a rotary hydraulic motor mounted on said frame and having a rotary shaft,

driving connections between said motor and said first-named shaft comprising two sets of serially arranged worm gearing to enable the shaft of said motor to extend longitudinally of said vehicle frame, and means for controlling said rotary hydraulic motor to effect lateral swinging of said arm to laterally shift the rear end of the drawbar, the worm gearing aforesaid serving to lock the drawbar in adjusted laterally shifted position.

2. In a road grading machine, the combination with a vehicle comprising a supporting frame, of a drawbar flexibly connected at its forward end to said frame, a grader blade carried by said drawbar, spaced-apart rock shafts mounted on said frame to extend longitudinally thereof to the top side of said frame, crank arms on the ends of said rock shafts, upright reciprocating hydraulic motors connected to the rear crank arms, extensible hangers connected between the forward crank arms and the rear end of said drawbar, a third rock shaft extending longitudinally and centrally of said frame below the top thereof, a crank arm on the forward end of said third rock shaft, an extensible link connecting said last-named crank arm with one side of the rear end of said drawbar, a rotary hydraulic motor mounted on said supporting frame between the crank arms at the forward ends of said first-named rock shafts, a double set of worm gear reductions between the rear end of said rotary hydraulic motor and the rear end of said third rock shaft, and means for controlling said hydraulic motors to secure individual operation thereof to effect adjustment of said grader blade laterally of the vehicle and in elevation and inclination.

FRANKLIN E. ARNDT.
